MEANS FOR THE PROPULSION OF SHIPS OR THE LIKE

Filed March 30, 1932

FIG. 1

FIG. 2

FIG. 5.

FIG. 3

UNITED STATES PATENT OFFICE

CARMELO M. FARRAGUTO, OF NEW YORK, N. Y.

MEANS FOR THE PROPULSION OF SHIPS OR THE LIKE

Application filed March 30, 1932. Serial No. 601,943.

This invention relates to new and useful improvements in a means for the propulsion of a ship or the like.

The invention has for an object the construction of a cam element for attachment upon the side of ship, and a casing rotatively supported outside of said cam element and having blades pivotally mounted at one of their ends and connected with pins engaging in said cam to cause said blades to move into operative positions as the casing turns.

Furthermore, as another object of this invention, it is proposed to construct the parts in a manner which will allow adjustment of the amplitude of motion of the blade.

The invention still further proposes the construction of a device of the class described which is of simple, durable construction, dependable in use and efficient in operation and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a vessel equipped with several of the propulsion devices.

Fig. 2 is a fragmentary sectional view taken on the line 2—2 of Fig. 1.

Fig. 3 is an enlarged detailed view of the cam element seen as though looking in the direction of the line 3—3 of Fig. 2.

Fig. 4 is an elevational view of the device with the cover plate removed, looking in the direction of the line 4—4 of Fig. 2.

Fig. 5 is a sectional view taken on the line 5—5 of Fig. 4.

Fig. 6 is a fragmentary enlarged sectional view taken on the line 6—6 of Fig. 4.

Fig. 7 is a sectional view taken on the line 7—7 of Fig. 4.

Fig. 8 is a similar view to Fig. 4 with the cover plate in place.

50 A ship 10 has been illustrated with a plu-

rality of propulsion means 11 according to this invention, mounted on the sides thereof below the water level. Each of the propulsion means comprises an element 12 in the form of a block having a suitable size of cam groove 13 and for attachment upon the side of the ship. A shaft 14 passes through the cam element and is connected with some source of rotations such as motors 15.

55 A casing 16 is located to the front of the element 12 and is fixed upon the shaft 14 so as to turn in unison with the shaft. The casing 16 comprises a pair of spaced discs clearly shown in Fig. 5. Each of these discs has a ring 17 rotatively mounted on its periphery and set screws 18 serve to hold these rings in various rotative positions. A plurality of plates 19 are arranged in end to end relation around the rings 17 and are pivotally mounted at their rear ends 20 upon the rings.

60 Slides 21 are arranged to slide radially between the discs 16. Each of these slides is provided with wheels 22 at its edges engaging a track 23 mounted upon one of the discs 16. A peg 24 is mounted upon each of the slides and these pegs project through radial slots 25 in one of the discs 16 and at their outer ends carry rollers 26 engaging in the cam groove 13.

65 Connecting rods 27 are pivotally mounted at one of their ends upon the slides 21 by the use of pegs 29. The other ends of the connecting rods 27 engage slides 30 arranged in tracks 31 longitudinally along the lengths of the blades 19. A set screw 32 is mounted in each of the blades and act against the slide 31 for holding the latter in any desired adjusted position.

70 The rings 17 have internal flanges 33 engaging peripheral grooves in the disc 16 to accomplish the rotative mounting of the rings upon the flanges. The blades 19 have portions 34 which extend beyond one of the discs 16 so as to provide greater width and consequently greater efficiency. The cam groove 13 is so constructed that the blades open up as they move from one side down to the bottom so as to efficiently propel the ship forwards. Fig. 4 clearly shows the positions in which the blades open. The blades

close so as to prevent drag as they leave the water. The degree of opening may be controlled by loosening the set screws 18 and 32 and turning the rings 17 relative to the discs so that the connecting rods 27 are connected with desired points upon the lengths of the blades. Then the set screws are turned in tight to maintain the parts in the new position.

10 In operation, a source of power causes the shafts 14 to turn and to turn the casing around the element 12. As the casing turns the projecting rollers 26 engaging in the groove 13 will direct the opening and close 15 of the blades 19 for the proper propulsion of the ship.

It is to be understood that the cam 13 may be lubricated in any suitable manner from the ship to reduce the friction, also that the material and proportions used in any improved device is such that will be best for the particular ship.

25 While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. Means for propulsion of ships and the like, comprising an element having a cam groove and for attachment upon the side of a ship or the like, a shaft through said element for connection with a source of rotation, a casing to the front side of said element and fixed upon said shaft and comprising spaced discs with peripheral rings and means for holding the rings in various rotative adjusted positions, blades in end to end relation arranged around said rings and pivotally mounted at their rear ends, slides radially mounted within said casing, pegs upon said slides projecting through openings in the casing and engaging into said cam groove, connecting rods pivotally mounted upon said slides, and means for connecting the outer ends of the connecting rods adjustably along the lengths of said blades.

2. Means for propulsion of ships and the like, comprising an element having a cam groove and for attachment upon the side of a ship or the like, a shaft through said element for connection with a source of rotation, a casing to the front side of said element and fixed upon said shaft and comprising spaced discs with peripheral rings and means for holding the rings in various rotative adjusted positions, blades in end to end relation arranged around said rings and pivotally mounted at their rear ends, slides radially mounted within said casing, pegs upon

said slides projecting through openings in the casing and engaging into said cam groove, connecting rods pivotally mounted upon said slides, and means for connecting the outer ends of the connecting rods adjustably along the lengths of said blades, said element comprising a block. 70

3. Means for propulsion of ships and the like, comprising an element having a cam groove and for attachment upon the side of a ship or the like, a shaft through said element for connection with a source of rotation, a casing to the front side of said element and fixed upon said shaft and comprising spaced discs with peripheral rings and means for holding the rings in various rotative adjusted positions, blades in end to end relation arranged around said rings and pivotally mounted at their rear ends, slides radially mounted within said casing, pegs upon said slides projecting through openings in the casing and engaging into said cam groove, connecting rods pivotally mounted upon said slides, and means for connecting the outer ends of the connecting rods adjustably along the lengths of said blades, the pivotal pintles supporting said blades engaging through said rings for holding the discs comprising the casing in spaced positions. 75 80 85 90 95

comprising the casing in spaced positions. 95
4. Means for propulsion of ships and the like, comprising an element having a cam groove and for attachment upon the side of a ship or the like, a shaft through said element for connection with a source of rotation, a casing to the front side of said element and fixed upon said shaft and comprising spaced discs with peripheral rings and means for holding the rings in various rotative adjusted positions, blades in end to end relation arranged around said rings and pivotally mounted at their rear ends, slides radially mounted within said casing, pegs upon said slides projecting through openings in the casing and engaging into said cam groove, connecting rods pivotally mounted upon said slides, and means for connecting the outer ends of the connecting rods adjustably along the lengths of said blades, said rings being provided with flanges engaging in grooves in the discs accomplishing the rotative mounting. 100 105 110 115

ing the rotative mounting.

5. Means for propulsion of ships and the like, comprising an element having a cam groove and for attachment upon the side of a ship or the like, a shaft through said element for connection with a source of rotation, a casing to the front side of said element and fixed upon said shaft and comprising spaced discs with peripheral rings and means for holding the rings in various rotative adjusted positions, blades in end to end relation arranged around said rings and pivotally mounted at their rear ends, slides radially mounted within said casing, pegs upon said slides projecting through open- 130

- ings in the casing and engaging into said cam groove, connecting rods pivotally mounted upon said slides, and means for connecting the outer ends of the connecting rods 5 adjustably along the lengths of said blades, each of said slides being provided with rollers along the edges engaging tracks on the casing to accomplish the radial sliding.
6. Means for propulsion of ships and the 10 like, comprising an element having a cam groove and for attachment upon the side of a ship or the like, a shaft through said element for connection with a source of rotation, a casing to the front side of said element and fixed upon said shaft and comprising spaced discs with peripheral rings and means for holding the rings in various 15 rotative adjusted positions, blades in end to end relation arranged around said rings and pivotally mounted at their rear ends, slides 20 radially mounted within said casing, pegs upon said slides projecting through openings in the casing and engaging into said cam groove, connecting rods pivotally mounted 25 upon said slides, and means for connecting the outer ends of the connecting rods adjustably along the lengths of said blades, said projecting pegs being provided with rollers engaging into said cam groove.
- 30 7. Means for propulsion of ships and the like, comprising an element having a cam groove and for attachment upon the side of a ship or the like, a shaft through said element for connection with a source of rotation, a casing to the front side of said element and fixed upon said shaft and comprising spaced discs with peripheral rings and means for holding the rings in various 35 rotative adjusted positions, blades in end to end relation arranged around said rings and pivotally mounted at their rear ends, slides 40 radially mounted within said casing, pegs upon said slides projecting through openings in the casing and engaging into said cam groove, connecting rods pivotally mounted 45 upon said slides, and means for connecting the outer ends of the connecting rods adjustably along the lengths of said blades, comprising slides mounted upon tracks on 50 said blades, said connecting rods being connected with said slides, and means for holding said slides in various adjusted positions.

In testimony whereof I have affixed my signature.

55 CARMELO M. FARRAGUTO.
